DOORSTOP

William Howard Phelps, Ralston, Nebr.

Application November 22, 1949, Serial No. 6,194

Term of patent 7 years

(Cl. D10—7)

To all whom it may concern:

Be it known that I, William Howard Phelps, a citizen of the United States, residing at Ralston, county of Douglas, and State of Nebraska, have invented a new, original, and ornamental Design for a Doorstop, of which the following is a specification, reference being had to the accompanying drawing, forming a part thereof, in which:

Figure 1 is a rear elevational view of a doorstop, showing my new design; Fig. 2, a side elevational view of the same; Fig. 3, a front elevational view; Fig. 4, a bottom plan view; and Fig. 5, a top plan view.

I claim:

The ornamental design for a doorstop, as shown.

WILLIAM HOWARD PHELPS.
